CABINET CONSTRUCTION UNIT

James G. Wells, Chicago, and Herbert C. Golz, Aurora, Ill., assignors to Elgin Metalformers Corporation, Elgin, Ill., a corporation of Illinois

Application October 11, 1957, Serial No. 48,065

Term of patent 14 years

(Cl. D26—5)

Fig. 1 is a front perspective view of a cabinet construction unit, showing our new design;

Fig. 2 is another front perspective view to an enlarged scale; and

Fig. 3 is another front perspective view thereof.

The back is conventional.

The broken line showing of other representative cabinet units with which the cabinet of this design may be associated is for illustrative purposes only.

We claim:

The ornamental design for a cabinet construction unit, substantially as shown and described.
